(57) **CLAIM**

The ornamental design for a container cap, as shown and described.

DESCRIPTION

FIG. 1 is a top perspective view of a container cap showing an embodiment of our new design;

FIG. 2 is a bottom perspective view thereof;

FIG. 3 is a front view thereof, the rear view being a mirror image of the front view;

FIG. 4 is a right side view thereof, the left side view being a mirror image of the right side view;

FIG. 5 is a top view thereof; and

FIG. 6 is a bottom view thereof.

FIG. 7 is a top perspective view of a container cap of showing an embodiment of our new design;

FIG. 8 is a bottom perspective view thereof;

FIG. 9 is a front view thereof, the rear view being a mirror image of the front view;

FIG. 10 is a right side view thereof, the left side view being a mirror image of the right side view;

FIG. 11 is a top view thereof; and

FIG. 12 is a bottom view thereof.

FIG. 13 is a top perspective view of a container cap of showing an embodiment of our new design;

FIG. 14 is a bottom perspective view thereof;

FIG. 15 is a front view thereof, the rear view being a mirror image of the front view;

FIG. 16 is a right side view thereof, the left side view being a mirror image of the right side view;

FIG. 17 is a top view thereof; and

FIG. 18 is a bottom view thereof.

FIG. 19 is a top perspective view of a container cap of showing an embodiment of our new design;

FIG. 20 is a bottom perspective view thereof;

FIG. 21 is a front view thereof, the rear view being a mirror image of the front view;

FIG. 22 is a right side view thereof, the left side view being a mirror image of the right side view;

FIG. 23 is a top view thereof; and

FIG. 24 is a bottom view thereof.

In the drawings, the broken lines depict unclaimed subject matter only and form no part of the claimed design.
